UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

CARBURETER.

1,260,956.

Specification of Letters Patent.

Patented Mar. 26, 1918.

Application filed June 8, 1914. Serial No. 843,330.

To all whom it may concern:

Be it known that I, REUBEN B. BENJAMIN, a citizen of the United States, residing at Chicago, in the county of Cook and 5 State of Illinois, have invented new and useful Improvements in Carbureters, of which the following is a full, clear, concise, and exact description, reference being had to the accompanying drawing, forming a 10 part of this specification.

My invention relates to carbureters for internal combustion engines.

It is one of the objects of my invention to provide a carbureter in which delivery 15 of the fuel to the mixing chamber in globules is avoided.

Further objects of my invention are to provide a carbureter in which undue wear in the moving parts is eliminated; to provide 20 a carbureter that is readily adjustable; and to provide a carbureter that is economical to manufacture and efficient in its operation.

A further object of my invention is to 25 provide an improved carbureter in which inertia means are provided for acting in opposition to the inertia of a suction controlled valve, whereby the bad effects due to the jarring of the carbureter will be minimized.

Additional objects and advantages of my 30 invention will be apparent from the following description taken in connection with the appended claims.

35 In the following specification and accompanying drawings I have described and illustrated a carbureter constructed in accordance with my invention but it is to be clearly understood that numerous changes 40 may be made in the form, construction and arrangement of the parts without departing from the spirit of my invention or exceeding the scope of the appended claims, the form of the invention herein disclosed 45 being merely one preferred embodiment thereof.

In the drawings:

Figure 1 is a cross sectional view of a 50 carbureter constructed in accordance with my invention, the section being taken on the line 1—1 of Fig. 3, looking in the direction of the arrows;

Fig. 2 is a top view showing part of the 55 rotary valve;

Fig. 3 is a cross sectional view taken on

the line 3—3 of Fig. 1, looking in the direction of the arrows;

Fig. 4 is a similar view taken on the broken line 4—4 of Fig. 1; and

Fig. 5 is a similar view taken on the line 50 5—5 of Fig. 3.

The carbureter has a fuel chamber 6 in which is a float member 7 carried by an arm 8 pivoted to the casing as at 9 and embracing a needle valve 10 which regulates the admission of the fuel from the tanks to retain the same at a substantially constant level. In the center of the fuel chamber the casing forms an air passage 11 which communicates with a main air intake port 70 12. This air passage is slightly contracted at the top and on the shoulders formed by the contracted portion seats a rotary valve 13, which, as will hereinafter appear, controls the admission of both the fuel and air 75 to a pipe 14, provided with a butterfly valve 15, leading to the intake manifold. The valve 13, which is mounted on a stem 16, is tapered substantially in the form of an inverted cone the lower portion of which 80 seats in cylindrical recess 17 formed in a projection 18 of the casing extending into the air passage 11.

To control the extent of the vertical displacement of the valve 13 a rod 19 is connected with a bifurcated lever 20 which is pivoted to the casing as at 21 and embraces a sleeve 22 in which the valve stem 16 rotates. The rod 19 is connected in any suitable manner with the accelerator and it will 90 be apparent that its depression will cause an increased vertical displacement of the valve. To prevent injury to the valve by any undue pressure on the rod 19 the displacement of the latter is limited by a stop 95 19^a comprising a screw which can be removed to allow the fuel chamber to be drained when desired.

Opening of the valve 13 is opposed by a coiled spring 23 embracing the rod 19 which 100 can be adjusted by the nut 24 to give the proper opposition to the suction on the valve under existing conditions.

The recess 17 is in effect a part of the fuel chamber as it is connected with the 105 main portion of the chamber by a large passage 25, a duct 26 leading to its upper portion, and a duct 27 leading to the lower portion where the conical end of the stem 16 seats. As the valve and valve stem thus 110

operate in the liquid fuel and as the rod 19 and lever 20 likewise operate in the fuel it will be seen that thorough lubrication is provided for practically all the parts that move in contact with other parts.

The valve 13 is rotated by means of a rotor 28 which comprises a disk mounted at the top of the valve on the stem 19 and has portions struck up to form a plurality of blades 29. The air passing up through the chamber or passage 11 strikes the blades 29 and causes the member 28 to rotate when the valve is opened, thus rotating the latter.

To regulate the proportion of air in the mixture, I provide an auxiliary air supply which enters the main mixture passage via a duct 30 leading from a port 31 and which is controlled by a spring pressed valve 32 which is opened by the suction of the cylinders. The amount of air thus admitted can be regulated by a rotatable member 33 bearing on the spring 34 of the valve, its manipulation causing the spring to oppose the opening of the valve to a greater or less degree. This member 33 may be connected to operating means on the dashboard of the vehicle in any suitable manner.

In operation the vacuum produced by varying speeds and performances of the engine causes the valve 13 to open vertically, thus opening the fuel and air passages proportionately, the flow of air striking the blades 29 and thus causing the valve 13 to rotate. Owing to the large diameter of the valve only a slight clearance is necessary and therefore the rotation will grind the fuel and cause it to flow out into the passage 11 in a very thin film and the centrifugal force spreads this film out over a large surface exposed to the air rushing in from the port 12. The air is preferably previously heated and so will heat the fuel as it passes along the surface of the valve so as to assist in the vaporizing action. In this way the air and fuel are mixed under the most favorable conditions and with none of the fuel in globules.

The relation of the amount of air to the fuel to meet variations in temperature, altitude, fuel conditions and the like is regulated by adjustment of the auxiliary air supply valve 32, which is also opened by the vacuum produced in the engine, by means of the member 33 as before described.

After the valve has opened to a position which gives the maximum air opening the valve can be raised still farther by the accelerator through the rod 19 and the lever 20. The end of the recess 17 in which the valve seats is in effect a nozzle and owing to the taper of the valve its increased vertical displacement opens this nozzle farther so as to increase the richness of the mixture. It will be noted that the inertia of the rod 19 and nuts 24 acts in opposition to the iner-

tia of the valve 13 and sleeve 22 to minimize the undesirable effect on the valve of the jarring of the vehicle. Without this counter-balancing feature if the carburetor is caused to move upwardly suddenly the inertia of the valve 13 and sleeve 22 would cause the valve to move toward closing position resulting in undesirable fluctuations of the valve. Similarly a sudden movement downward of the carburetor without the counter-balancing feature would cause the valve to be opened wider. With the counter-balance, however, the movement up and down of the carburetor will have little effect on the operation of the valve 13.

Having thus described my invention what I claim as new and desire to secure by Letters Patent is:

1. A carburetor comprising a fuel supply, an outlet port therefrom, an air passage having a port, and valve means movable as a unit comprising a continuously tapered member, the smaller part of which extends into said fuel port to control the flow of fuel, and the larger part of which co-operates with said air port to control the flow of air, and an air motor in said air passage connected to said valve means for rotating it.

2. In a carburetor, the combination with a fuel supply and an air supply, of means for controlling the flow of fuel from said supply, comprising a suction operated valve mounted for movement with respect to its seat, and inertia means for preventing relative movement between said valve and seat due to the movement of the carburetor, whereby fluctuation of the valve due to the movement of the carburetor is prevented, said means comprising a mass of substantially equal weight to that of the valve connected to said valve for counterbalancing the same.

3. In a carburetor, the combination with a fuel supply and an air supply, of means for controlling the flow of fuel from said supply, comprising a suction operated valve mounted for movement with respect to its seat, and inertia means for preventing relative movement between said valve and seat due to the movement of the carburetor, whereby fluctuation of the valve due to movement of the carburetor is prevented, said means comprising a lever of the first class having one end connected to the valve, and a mass of substantially equal weight connected to the other end of the lever for counterbalancing the valve.

4. In a carburetor, the combination with a fuel-supply and an air-supply of means for controlling the flow from one of said supplies comprising a suction-operated valve mounted for movement with respect to its seat, and inertia means for preventing relative movement between said valve and seat due to the movement of the carburetor,

whereby fluctuation of the valve due to movement of the carbureter is prevented. said means comprising a mass the moment of inertia of which is substantially equal and opposite to that of the valve, connected to said valve for counterbalancing it.

In witness whereof, I have hereunto sub-

scribed my name in the presence of two witnesses.
